UNITED STATES PATENT OFFICE

FREDERICK MADISON MEIGS, OF WILMINGTON, DELAWARE, ASSIGNOR TO E. I. DU PONT DE NEMOURS & COMPANY, OF WILMINGTON, DELAWARE, A CORPORATION OF DELAWARE

PROCESS FOR PREPARING ORGANIC FLUORINE COMPOUNDS

No Drawing.

Application filed June 15, 1931. Serial No. 544,712.

This invention relates to a process for the preparation of organic compounds containing fluorine, and more particularly it relates to a process for the preparation of organic compounds containing fluorine atoms attached directly to the carbon atoms of aromatic nuclei.

Among the various methods disclosed in the prior art for preparing organic fluorine compounds there may be mentioned the process of Le Fevre and Turner (J. Chem. Soc., 1930, 1158) wherein an aryl diazonium chloride is converted, by means of sodium borofluoride, to the aryl diazonium borofluoride which yields the aryl fluoride by thermal decomposition. In this process, however, and in other processes of which I am aware, the precipitation of the aryl diazonium borofluoride has been conducted in the presence of a large excess of acid which has resulted in yields considerably lower than obtained through the practice of the present invention.

This invention has as an object the preparation of organic fluorine compounds in which the fluorine atom (or atoms) is attached directly to the carbon atoms of aromatic nuclei. A further object is an improvement in the yield of the intermediate aryl diazonium borofluorides. A still further object is the simplification of the preparation of these compounds so that the process becomes both industrially applicable and economically feasible.

These objects are accomplished by the use of a medium of low hydrogen-ion concentration during the conversion of the diazotized amine into the aryl diazonium borofluoride.

The following equations, in which an organic radical is represented generally by the phenyl group, indicate the diazotization of the amine salt, the formation of the aryl diazonium borofluoride, and the thermal decomposition of the latter:

In conducting the diazotization reaction of Equation (1) it is necessary, in order to prevent a coupling of the diazonium salt with

the amine salt, that the acid be present in excess of the amount theoretically required by the equation. While the presence of only a slight excess of acid is necessary, it is the general practice to add the acid to substantial excess inasmuch as there is usually no purpose or need for adding the calculated quantity of acid required to just bring the solution to the acid side of neutrality. The usual practice of adding a considerable excess of acid in the diazotizing reaction has been followed in prior processes for the manufacture of organic fluorides in accordance with the above formulæ with the result that the diazonium borofluoride in Equation (2) has been precipitated in a medium of high hydrogen-ion content. I have discovered that much higher yields of the diazonium borofluoride, and hence of the organic fluoride, are obtained when the reaction indicated by Equation (2) is carried out in a medium of low hydrogen-ion concentration.

A hydrogen-ion concentration sufficiently low for the precipitation of the diazonium borofluoride in the higher yields which characterize the present invention may be obtained by forming the diazonium salt with substantially the minimum amount of acid which will prevent the coupling of the amine and diazonium salt, or by adding alkali after formation of the organic diazonium salt to give a neutral or alkaline solution when the diazotization has been carried out with excess acid, and then using as a precipitant a borofluoride compound, as sodium borofluoride, which does not raise the hydrogen-ion content of the solution beyond the desired value. In case the diazotization reaction of Equation (1) has been carried out in the presence of excess acid the alkali mentioned above may also be added after the sodium borofluoride to keep the hydrogen-ion concentration in the reaction of Equation (2) below the desired value and drive the reaction of Equation (2) to the right because, although a precipitate has formed, the precipitation of aryl diazonium borofluoride is not complete in solutions of high hydrogen-ion concentration.

One of the most convenient methods for

maintaining low hydrogen-ion concentration during the precipitation of the diazonium borofluorides is the use of sodium borofluoride as a precipitant. When borofluoric acid is used as the precipitant free acid is formed by double decomposition and the hydrogen-ion concentration is built up during the reaction. An important feature of the present invention consists, therefore, in using sodium borofluoride as a precipitant in conjunction with that part of the present process which comprises the utilization of a solution of an organic diazonium salt of low hydrogen-ion concentration.

In order to obtain the high yields of organic diazonium borofluoride, and consequently of the corresponding organic fluorine compound, the hydrogen-ion concentration of the solution of organic diazonium salt during precipitation of the organic diazonium borofluoride should not be allowed to rise above 1 mole per liter. I prefer to keep the hydrogen-ion concentration below 0.3 moles per liter inasmuch as the yields obtained are markedly higher than were obtained by prior methods. The hydrogen-ion concentration may vary from the values given to the minimum possible value represented by the slight excess of acid necessary for the formation of the organic diazonium salt. Or, if the hydrogen-ion content is reduced to the proper value by neutralizing the excess acid after the formation of the organic diazonium salt, the lower limit of hydrogen-ion content includes neutral and alkaline solutions. Inasmuch as it is practically impossible to determine the exact-ion concentrations due to the difficulty of making measurements in solutions of easily oxidizable or reducible substances, the values given herein represent only the total "available" hydrogen-ion concentration in moles per liter (assuming complete ionization) after the precipitate of the aryl diazonium borofluoride has been formed. While the true hydrogen-ion concentration may differ considerably from these values it is pointed out that the true hydrogen-ion concentration cannot exceed the values given.

The following examples are illustrative of the methods that may be used in carrying out the invention:

Example I

9.3 grams of aniline dissolved in 18.3 cc. of concentrated hydrochloric acid and 10 cc. of water is diazotized with a solution of 7 grams of sodium nitrite dissolved in 20 cc. of water. The temperature is maintained below 10° C. 30 grams of a 40% solution of sodium borofluoride is added to the clear phenyl diazonium solution. The precipitated phenyl-diazonium borofluoride is collected on filter paper and dried in vacuo under reduced pressure. The yield of phenyl diazoni-

um borofluoride is 16.2 grams or 84.8% of theory on the basis of aniline. Quantitative decomposition of the borofluoride to fluorobenzene is accomplished by heating the salt to 90-110° C. The boron trifluoride which is evolved is recovered by solution in a suspension of sodium fluoride in water. As the boron trifluoride is absorbed the suspension gradually becomes a clear solution of sodium borofluoride.

The hydrogen-ion concentration after the precipitate of borofluoride had been formed was 0.25 moles per liter.

Example II

A solution of 46 grams of benzidine in 500 cc. of water and 40 cc. of concentrated hydrochloric acid is added to a solution of nitrous acid prepared by the addition of 52 cc. of concentrated hydrochloric acid to 35 grams of sodium nitrite dissolved in 400 cc. of water and ice. A few grams of butyl alcohol is added to prevent foaming. The temperature of the diazotization mixture is kept below 10° C. 50 grams of 40% solution of sodium borofluoride is added to precipitate the diphenyl tetraazonium borofluoride. The salt is brought on a filter and dried under reduced pressure. The yield or pure salt is 82 grams or 86.4% on the basis of benzidine. Quantitative conversion to difluorodiphenyl is accomplished by heating the dry salt. The boron trifluoride evolved is absorbed in 40% sodium hydroxide. On addition of an equivalent amount of hydrofluoric acid this solution is converted to a solution of sodium borofluoride.

The hydrogen-ion concentration after the precipitate of borofluoride had been formed was 0.08 moles per liter.

Example III

A solution of 72 grams of beta-naphthylamine in 250 cc. of water and 200 cc. of concentrated hydrochloric acid is treated with a solution of 35 grams of sodium nitrite in 120 cc. of water. The temperature of the reaction mixture is kept below 10° C. 165 grams of a 40% solution of sodium borofluoride is added to the clear solution of diazonium salt. A solution containing 50 grams of sodium hydroxide is added to reduce the hydrogen-ion concentration and complete the precipitation of the diazonium borofluoride. The precipitate is collected on a filter and dried under reduced pressure. The yield of beta-naphthyl diazonium borofluoride is 97.4% of theory on the basis of the amine. Thermal decomposition of the diazonium borofluoride to beta-fluoronaphthalene is almost quantitative. The boron trifluoride which is evolved may be absorbed in a solution of an aryl diazonium fluoride, with the precipitation of the corresponding aryl diazonium borofluoride.

The hydrogen-ion concentration after the precipitate of borofluoride had been formed was 0.14 moles per liter.

While the preferred method of carrying out the invention consists in precipitating the aryldiazonium fluoride from solutions of low hydrogen-ion concentration by means of sodium borofluoride, the objects of the invention may be attained by following several different modes of procedure. For instance, the aryldiazonium borofluoride may be precipitated from either an acid or neutral solution of the diazonium salt with borofluoric acid and sodium hydroxide added to remove hydrogen-ions formed by substituting this precipitant for sodium borofluoride in Equation (2), together with hydrogen-ions that may have been originally present in the solution of the diazonium salt, and thereby reduce the hydrogen-ion concentration to shift the equilibrium of the reaction in the direction favoring a high yield of the aryldiazonium borofluoride and consequently of the arylfluoride of Equation (3). If desired the sodium hydroxide may be added, in certain cases, to the solution of diazonium salt before precipitating with the borofluoric acid, the alkali being present in such amount as will reduce the hydrogen-ion concentration of the reaction mixture to the proper value. These methods in which the precipitation is with borofluoric acid accompanied with the use of sodium hydroxide are less economical and convenient than using the equivalent amount of the sodium borofluoride as a precipitant. Sodium borofluoride is also desirable because of its high solubility as compared with other borofluorides.

Example IV

This example illustrates the use of a mixture of a borofluoride and borofluoric acid as a precipitant.

A solution in 50 cc. of water containing 0.1 mole of phenyldiazonium chloride and less than 0.02 mole of hydrochloric acid is treated with a solution containing 0.11 mole of a mixture consisting of 50% sodium borofluoride and 50% borofluoric acid. The yield of the diazonium borofluoride is 14.0 grams or 78.1% of theory. If, however, 0.055 mole of sodium hydroxide in solution is added before the precipitate is brought on a filter, the yield is increased to 84% of theory as in Example I.

The hydrogen-ion concentration was 1.13 moles per liter before the addition of alkali and 0.28 moles per liter after the addition of alkali.

The mixture of sodium borofluoride and borofluoric acid referred to above is prepared by the treatment of borax with the calculated amount of hydrofluoric acid to convert all the boron to the borofluoride complex.

Another means of obtaining low hydrogen-

ion concentration during formation of the intermediate diazonium borofluoride is through the use of hydrofluoric acid in the diazotization solution and the subsequent addition of gaseous borontrifluoride for the formation of borofluoride ion and precipitation of the diazonium borofluoride. The equations are:

The following example is illustrative of this method of carrying out the invention: 80

Example V

A solution of 9.3 grams of aniline dissolved in 9.2 cc. of concentrated hydrochloric acid, 5 cc. of concentrated hydrofluoric acid, and 10 cc. of water is treated with a solution of 7 grams of sodium nitrite in water. The resulting clear solution of phenyldiazonium chloride is treated with gaseous boron trifluoride prepared by any of the methods known in the art, or obtained during decomposition of an aryldiazonium borofluoride, until the precipitation of phenyldiazonium borofluoride is complete. The salt is brought in a filter, dried, and decomposed as above. 95

The hydrogen-ion concentration after the precipitate of borofluoride had been formed was 0.92 moles per liter.

The diazotization with hydrofluoric acid may be followed by the addition of borax instead of the borontrifluoride for the precipitation of the aryldiazonium borofluoride, a sufficient excess of hydrofluoric acid being allowed for conversion of the boron to the borofluoride complex. 100

Another method of procedure is to conduct the diazotization reaction in the presence of sodium borofluoride while maintaining the hydrogen-ion concentration within the desired limits as indicated in the following example: 110

Example VI

9.3 grams of aniline dissolved in a solution containing 0.22 mole of available hydrogen-ion and 0.11 mole of available borofluoride ion (for instance 18.3 cc. of concentrated hydrochloric acid and 12 grams of sodium borofluoride) is diazotized with a solution of 7 grams of sodium nitrite in water. During diazotization the temperature of the mixture is maintained below 30° C. Phenyl-diazonium borofluoride precipitates out as the diazotization progresses and is frozen out at the completion of the reaction. The salt is dried and decomposed in the usual manner. 120

The hydrogen-ion concentration after the precipitate of borofluoride had been formed was 0.41 mole per liter. 130

A feature of this example is the relatively high temperature allowable during diazotization which is possible due to the fact that the insoluble and relatively stable diazonium 5 borofluoride is formed as rapidly as the amine is diazotized.

A number of the modifications are described in the examples and many others will suggest themselves to those skilled in 10 the art. Among these may be mentioned the use of any soluble salt of borofluoric acid as a precipitant. In the diazotization reaction, sulfuric and other known diazotizing acids may be used.

15 The effect of the hydrogen-ion concentration on the yield of the diazonium borofluoride is clearly shown by the following results which were obtained under similar conditions except for the concentration of 20 the hydrogen-ion during precipitation. In each case, the solution of phenyldiazonium chloride was prepared by treatment of a solution of 9.3 grams of aniline in 18.3 cc. of concentrated hydrochloric acid and 10 cc. of 25 water with a solution of 7 grams of sodium nitrite dissolved in 20 cc. of water. This is equivalent to 0.1 mole of aniline and 0.22 mole of acid, an excess of 0.02 mole of acid.

30	Precipitant	Hydrogen-ion in moles per liter	Yield Percent
35	1. 0.11 mole of HBF_4 .	1.96	67
	2. 0.11 mole of a solution of 50% HBF_4 and 50% NaBF_4 .	1.09	78.1
	3. 0.11 mole of a solution containing 25% HBF_4 and 75% NaBF_4 .	0.67	80.1
	4. 0.11 mole of NaBF_4 .	0.26	84.3

40 Inasmuch as certain compounds will give higher yields than others, comparisons of the effect of lowered hydrogen-ion concentration must be made with identical compounds. However, lowering the hydrogen-ion concentration in a given preparation increases 45 the yield of that compound over that obtainable under conditions of higher hydrogen-ion concentration. Another illustration of the high yields possible through the practice of the present invention may be had by 50 comparing the 44.2% yield from benzidine obtained in the LeFevre and Turner citation mentioned with a hydrogen-ion concentration of 1.09 and the yield obtained in Example II herein which was 86.4% with a hydrogen-ion concentration of 0.08.

55 As many apparently widely different embodiments of this invention may be made without departing from the spirit and scope thereof, it is to be understood that I do not limit myself to the specific embodiments thereof except as defined in the following claims.

I claim:

60 1. A process of making organic fluorine compounds which comprises precipitating an

organic diazonium borofluoride from solutions having a hydrogen-ion concentration not greater than one mole per liter, and converting the organic diazonium borofluoride into organic fluoride. 70

2. A process of making aromatic fluorine compounds which comprises precipitating an aryldiazonium borofluoride from solutions having a hydrogen-ion concentration not greater than one mole per liter, and converting the aryldiazonium borofluoride into aryl 75 fluoride.

3. A process of making aromatic fluorine compounds which comprises precipitating an aryldiazonium borofluoride from solutions having a hydrogen-ion concentration not greater than 0.3 mole per liter, and converting the aryldiazonium borofluoride into aryl 80 fluoride.

4. A process of making aromatic fluorine compounds which comprises precipitating with sodium borofluoride an aryldiazonium borofluoride from solutions having a hydrogen-ion concentration not greater than one mole per liter, and converting the aryldiazonium borofluoride into aryl 85 fluoride. 90

5. A process of making aromatic fluorine compounds which comprises precipitating with sodium borofluoride an aryldiazonium borofluoride from solutions having a hydrogen-ion concentration not greater than 0.3 mole per liter, and converting the aryldiazonium borofluoride into aryl 95 fluoride.

6. A process of making aromatic fluorine compounds which comprises preparing a solution of aryldiazonium salt, adding a borofluoride precipitant, maintaining the hydrogen-ion concentration of the solution during precipitation below one mole per liter with alkali, and converting the precipitated aryldiazonium borofluoride formed into aryl 100 fluoride. 105

7. A process of making aromatic fluorine compounds which comprises diazotizing an aryl amine hydrochloride with sodium nitrite and hydrochloric acid to form a solution of aryldiazonium chloride, precipitating aryldiazonium borofluoride with sodium borofluoride, the hydrogen-ion concentration of said solution during precipitation being not greater than one mole per liter, and forming aryl fluoride from the aryldiazonium borofluoride by thermal decomposition. 110

8. A process of making aromatic fluorine compounds which comprises diazotizing an aryl amine salt in the presence of the minimum quantity of acid which will prevent coupling of the diazonium salt formed with the amine salt, precipitating aryldiazonium borofluoride with sodium borofluoride, and converting the aryldiazonium borofluoride into aryl 115 fluoride. 120

9. A process of making aromatic fluorine compounds which comprises preparing a solution of diazonium salt having an available hydrogen ion concentration of less than one 130

mole hydrogen ion per liter, precipitating aryl diazonium borofluoride, and converting the aryl diazonium borofluoride into aryl fluoride.

- 5 10. A process of making aromatic fluorine compounds which comprises diazotizing an aryl amine in the presence of sodium borofluoride and maintaining the hydrogen-ion concentration of the diazotization solution below one mole per liter, and converting the aryl diazonium borofluoride into aryl fluoride.
- 10 11. A process of making aromatic fluorine compounds which comprises diazotizing an aryl amine in the presence of hydrofluoric acid, maintaining the hydrogen ion concen-

tration of the solution below one mole per liter, precipitating aryl diazonium borofluoride and converting the latter into aryl fluoride.

12. A process of making aromatic fluorine compounds which comprises diazotizing an aryl amine in the presence of hydrofluoric acid, maintaining the hydrogen ion concentration of the solution below one mole per liter, precipitating aryl diazonium borofluoride with boron trifluoride and converting the latter into aryl fluoride.

In testimony whereof, I affix my signature.
